UNITED STATES PATENT OFFICE.

MORTON E. PUGH, OF SUNFLOWER, MISSISSIPPI.

EXCAVATOR.

SPECIFICATION forming part of Letters Patent No. 498,364, dated May 30, 1893.

Application filed July 7, 1891. Renewed November 3, 1892. Serial No. 450,885. (No model.)

To all whom it may concern:

Be it known that I, MORTON E. PUGH, of Sunflower, in the county of Coahoma and State of Mississippi, have invented certain new and useful Improvements in Excavators; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This invention relates to certain improvements in excavating apparatus and more particularly to improvements on my former patent No. 379,722, dated March 20, 1888, and having relation to an excavating apparatus comprising an endless traveling cable, having operating means, and to which the digging or excavating implements are detachably secured and by which they are drawn.

The object of this invention is to provide improved means whereby the endless operating cable can be quickly and easily adjusted and moved laterally or horizontally without stopping the motion of the cable. This object is accomplished by, and this invention consists in, certain novel features of construction and in combinations of parts more fully described hereinafter and particularly pointed out in the claims.

Referring to the accompanying drawings:—Figure 1, is a plan view, showing the operating or driving cable and the supporting and adjusting frames thereof. Fig. 2, is an end view of one of said frames with parts broken away. Figs. 3, and 4, are views of details.

In the drawings reference letter *a*, indicates an endless operating cable. This cable is so mounted and arranged that it will travel above the surface of the earth which is to be operated upon. As set forth in my before-mentioned patent, the digging or excavating implements *a'* are detachably secured to this cable and are drawn thereby across the portion of the earth to be excavated and to the place where the earth is to be deposited. Of course, as the work progresses, the cable has to be shifted to different positions. The object of my present invention is to provide im-

proved means to quickly and easily accomplish this shifting without stopping the motion of the cable.

The truck or vehicle *b* is provided with a large grooved driving pulley *c*, horizontally arranged upon a suitable vertical shaft *c'* carried by the truck and connected with suitable driving means, not here shown. The cable is held in engagement with an extended portion of the periphery of this driving pulley by means of the two idler pulleys *d*, carried by arms *e*, from the truck and holding the cable upon the driving pulley, as shown in Fig. 1.

At every point where it is desired to have the operating cable change its direction, a pulley *f*, is provided, around which the cable passes; the cable, preferably, being so arranged as to have four corners or turns; although, of course, it can be arranged in any suitable manner other than to make four corners. Each corner guide pulley is carried by a suitable elevated frame-work comprising supporting beams *g*, braced and strengthened in any suitable manner and the two horizontal guide beams or tracks *h*, located a suitable distance apart and extending in the direction in which it is desired to cause the line of excavation to proceed. Each guide pulley *f*, is carried by an arm *i*, extending horizontally between said guide beams *h* and carried by the two rollers *j*, traveling on the outer sides of the track beams *h*. The said arm *i*, is mounted on the axle of the two rollers *j*, and has the joint *k* between the rollers *j*, and pulley *f*, to permit vertical movement of said pulley.

The inner end of one of the sections of arm *i*, has a vertical series of horizontal apertures *k''*, and the inner end of the opposite section has one aperture to separately register with said apertures of the series *k''*, as it is raised and lowered, and the outer section of the arm *i*, is held in the desired vertical adjustment by the horizontal removable pivot pin *k'*. These parts *i*, and *j*, so carry the pulley that it can be horizontally adjusted the length of the track beams, thereby moving the operating cable horizontally over a corresponding surface of ground. A similar frame and adjusting means are provided for each corner pulley. The corner frames are preferably ar-

ranged in pairs, as shown, with the track beams of each pair extending in the same direction.

Of course, the frame supporting the parts 5 can be greatly varied in construction, particularly when made of iron.

In order to always keep the cable taut and to be able to move it horizontally while continuing to operate, the two guide pulleys at 10 consecutive corners on the same side of the excavation are arranged to move simultaneously. In order to accomplish this, the outer ends of the two frames are provided with stationary mounted pulleys *l*, in substantially 15 the same planes with the operating cable guide pulleys; and an adjusting cable *n*, is provided. At one end, it is secured to the arm *o*, from the movable frame *i*, of one of the guide pulleys; and, passing around the 20 pulley *l*, of the supporting frame thereof, and thence extending to and around the stationary mounted pulley *l*, on the opposite supporting frame. At its opposite end it is secured to a corresponding arm *o*, of the opposite 25 site guide pulley; so that, when the guide pulley at one end is moved toward the right, the guide pulley at the other corner will be correspondingly moved toward the right. The adjusting cable is operated by suitable means 30 to move the guide pulleys toward the right or left; such means, preferably, consisting of the horizontal worm wheel *p*, rigid with the shaft of one of the guide pulleys for the adjustable cable, and the worm *q*, meshing with said 35 worm wheel and provided with a suitable handle *q'* or other rotating means, whereby the operator can easily move the adjusting cable. Ordinarily, four guide pulleys are provided for the operating cable and are arranged and connected in two pairs, as shown. 40

The many and great advantages of this construction are obvious. The traveling cable can be quickly and easily adjusted horizontally.

45 It is evident that various changes might be made and resorted to in the form, arrangements and constructions of the parts herein described, without departing from the spirit and scope of my invention. Hence, I do not 50 wish to limit myself to the peculiar construction herein set forth.

What I claim is—

1. In an excavating apparatus, the combination of the endless operating cable, the horizontal guide pulleys therefor, adjustable horizontally independently of the drive wheel to shift the cable while moving the truck or vehicle, the large horizontal drive wheel for said cable mounted on such truck or vehicle, and 60 the two idler pulleys located on the opposite sides of said drive pulley and holding the operating cable in contact with an extended portion of the periphery of said drive pulley, substantially as described.

65 2. The combination with the endless operating cable, guide pulleys therefor, movable frames for such guide pulleys provided with

rollers, horizontal guides for each movable frame upon which the rollers travel, supporting frames carrying such guides, and an adjusting cable connecting said movable frames so that they move together horizontally, and means, substantially as described, to move the adjusting cable to horizontally shift the said guide pulleys and the operating cable. 70

3. The combination with the endless operating cable, operating means therefor, two guide pulleys for such cable, movable frames provided with rollers and carrying such guide pulleys, horizontally arranged track rails for 80 each movable frame upon which the rollers thereof travel, supporting frames therefor, and an adjustable cable connecting said two movable frames so as to move the two guide pulleys simultaneously in the same direction, 85 and worm gearing and a pulley to operate said adjusting cable, substantially as set forth. 95

4. The combination with the operating cable, a horizontal guide pulley therefor, an upright frame, a pair of separate parallel horizontal tracks carried by such frame, a horizontal frame to each guide pulley extended between said two guide tracks and provided with a pair of rollers on its outer end traveling on said tracks, said horizontal frame having a joint so arranged that the guide pulleys can swing vertically, substantially as set forth. 95

5. The excavating apparatus consisting of the endless operating cable, the horizontally rotating drive wheel mounted on a vertical axis, the corner guide pulleys, horizontally adjustable carriers for said pulleys, and stationary supports for said carriers on which the same are adjusted, and gearing and connections connecting the corner pulleys in pairs 100 so that each pair of corner pulleys can be adjusted together independently of the drive pulley and while the cable is traveling, substantially as described.

6. An excavating apparatus consisting of the endless operating cable, the horizontally rotating drive pulley mounted on a vertical axis, means for holding the cable in contact with a portion only of said pulley, the corner guide pulleys having horizontally movable 115 carriers, supports for said carriers, means substantially as described whereby said carriers can be adjusted to horizontally shift the corner pulleys and cable, and whereby said corner pulleys are held in the desired position. 120

7. In an excavating apparatus, the endless operating cable, corner guide pulleys therefor provided with suitable supports, the horizontally rotating drive pulley mounted on a vertical axis, and means substantially as described for holding said cable in contact with a portion of the periphery of said pulley, substantially as described. 125

8. An excavating apparatus consisting of the operating cable and driving means therefor, corner guide pulleys for said cable, horizontally adjustable carriers for said pulleys, horizontally elongated supporting frames for said carriers, and gearing and connections 130

connected to each supporting frame and the carrier thereon to horizontally adjust the carrier on the frame and hold the same in the desired position, substantially as described.

5 9. In an excavating apparatus, the combination of the operating cable and means for actuating the same, corner guide pulleys for said cable, carriers for said pulleys, horizontally elongated stationary supporting frames for said carriers on which the carriers are horizontally adjustable in parallel directions, said carriers being connected in pairs and arranged to move together in the same direction, and means substantially as described for holding the carriers in the desired adjustment and for adjusting the same, as and for 15 the purposes set forth.

10 10. In an excavating apparatus, the combination of the operating cable, corner guides, 20 carriers therefor, the stationary supporting frames having horizontally elongated parallel tracks, said carriers being confined and horizontally adjustable on said tracks, an ad-

justing cable connecting each pair of carriers and moving the same together in the same direction, and means for holding the carriers in the desired adjustment substantially as described. 25

11. In an excavating apparatus the combination of the operating cable, the corner guide 30 pulleys, the stationary supporting frames, each provided with a pair of separated parallel horizontal tracks, the carrier for each corner pulley consisting of the arm extending between said tracks and provided with rollers operating on the same, said pulleys connected in pairs substantially as described and provided with holding and adjusting means. 35

In testimony that I claim the foregoing as my own I affix my signature in presence of two witnesses.
